CLAIM

The ornamental design for a modular highchair, substantially as shown and described.

DESCRIPTION

FIG. 1 is a first perspective view of a modular highchair according to the design.

FIG. 2 is a second perspective view of the highchair of FIG. 1.

FIG. 3 is a front view of the highchair of FIG. 1.

FIG. 4 is a back view of the highchair of FIG. 1.

FIG. 5 is a side view of the highchair of FIG. 1, the opposite side view being substantially a mirror image thereof.

FIG. 6 is a top view of the highchair of FIG. 1; and,

FIG. 7 is a bottom view of the highchair of FIG. 1.

The broken line portions of the drawing figures are included to show portions of the article or environment that are not part of the claimed design.

1 Claim, 6 Drawing Sheets
